UNITED STATES PATENT OFFICE.

FRANKLIN M. BOWERS AND JOSEPH L. DICKELMAN, OF FOREST, OHIO.

EAVES-TROUGH.

SPECIFICATION forming part of Letters Patent No. 508,366, dated November 7, 1893.

Application filed June 28, 1893. Serial No. 479,028. (No model.)

To all whom it may concern:

Be it known that we, FRANKLIN M. BOWERS and JOSEPH L. DICKELMAN, citizens of the United States, residing at Forest, in the county 5 of Hardin and State of Ohio, have invented certain new and useful Improvements in Eaves-Troughs; and we do declare the following to be a full, clear, and exact description of the invention, such as will enable others skilled in the art to which it appertains to make and use the same, reference being had to the accompanying drawings, and to the letters of reference marked thereon which form a part of this specification.

This invention relates to certain new and useful improvements in eaves-troughs of that class in which the trough is made up of sections or lengths detachably united and provided with a fold or doubled portion to form a guide for the adjoining section or length.

It has for its objects among others to provide an improved eaves-trough of this character in which the sections or lengths can be more readily joined and when joined will be stronger and less liable to become separated. In forming the sections or lengths we make a bead or roll upon both edges, and at one end of each section or length this bead or roll is formed with extensions or lips which serve to guide the entering section into proper position and which serve also to aid in strengthening the joint. These extensions or lips are important in guiding the end of one section into the groove formed by the folded over end of the section on which the extensions or lips are formed.

Other objects and advantages of the invention will hereinafter appear and the novel features thereof will be specifically defined by the appended claims.

The invention in the present instance resides in the peculiar combinations, and the construction, arrangement and adaptation of parts, all as more fully hereinafter described, 45 shown in the drawings, and then particularly pointed out in the claims.

The invention is clearly illustrated in the accompanying drawings, which, with the letters of reference marked thereon, form a part 50 of this specification and in which—

Figure 1 is a view showing the adjacent

ends of two sections or lengths about to be united. Fig. 2 is a perspective view of the end of one section or length, showing the lips or extensions. Fig. 3 is a vertical cross 55 section through a section or length through the folded portion.

Like letters of reference indicate like parts throughout the several views.

Referring now to the details of the drawings by letter, A designates a section or length of the trough which is formed upon both edges, with the roll or bead a formed thereon in any well known way, and at one end of the section or length this bead or roll, is extended 60 beyond the end of the body portion of the trough to form the lip or lips a' which are preferably tapered or beveled from their upper sides downward and toward the opposite end of the trough as shown. The body portion of the trough at this end is formed with a groove b to receive the end of the adjacent section or length B, and this groove is formed by folding a portion of the metal of the body portion upon itself to form the groove. The 65 portion which is to be folded is somewhat narrower than the body portion proper as seen so that when it is folded upon itself at the end of the body portion as shown at c and thence extended a proper distance to 70 toward the other end and then bent upon itself as seen at d, the same will terminate within the space between the rolls or beads on the trough whereby the rolls or beads may be formed independent of the folded 75 portion, either before or afterward. The free end of the folded portion is extended beyond the end of the body portion as seen at e to form a guide and support for the end of the adjacent section or length.

The operation will be readily understood. In uniting the sections or lengths the end of the one is first brought opposite the groove in the other, the extensions or lips on the rolls or beads of the latter serving to center 80 the entering end and at the same time strengthening the joint.

The trough may be further provided with the transverse brace bars D if desired which may be secured thereto in any of the well 85 known ways.

What is claimed as new is—

The herein described eaves trough section formed of a single piece with beads or rolls at opposite edges, and at one end with a groove *b* and a folded portion or tongue narrower than the body portion between the beads or rolls with its free end extending beyond the end of the body portion, and the side rolls or beads extended beyond the end of the body portion and beyond the end of the tongue and tapered from their upper sides down-

ward and toward the end of the trough, substantially as shown and described.

In testimony whereof we affix our signatures in presence of two witnesses.

FRANKLIN M. BOWERS.
JOSEPH L. DICKELMAN.
